UNITED STATES PATENT OFFICE.

JOHN FRED HILDEBRAND, OF LOS ANGELES, CALIFORNIA.

DESIGN FOR AN ASH TRAY.

Application filed October 1, 1927. Serial No. 23,595. Term of patent 7 years.

To all whom it may concern:

Be it known that I, JOHN FRED HILDEBRAND, a citizen of the United States, residing at Los Angeles, in the county of Los Angeles, State of California, have invented a new, original, and ornamental Design for Ash Trays, of which the following is a specification, reference being had to the accompanying drawing, forming a part thereof.

In the drawing, Fig. 1 is a front elevation showing an ash tray embodying my new design; Fig. 2 is a side elevation of the same; and Fig. 3 is a top plan view.

I claim:

The ornamental design for an ash tray as shown.

JOHN FRED HILDEBRAND.
